STOKER

Warren Dean Burton, Goshen, Ind., assignor to
Combustioneer, Inc., Goshen, Ind., a corpora-
tion of Illinois

Application December 29, 1930, Serial No. 505,230

7 Claims. (Cl. 110—47)

This invention relates to mechanical stokers for furnaces and more particularly to those of the underfeed type wherein coal is fed into the furnace by a conveyor screw and forced upwardly thereby into a retort where it is consumed.

When stokers of the above character are applied to Scotch marine boilers, it is necessary that the retort be made relatively long and narrow. A correspondingly long section of the conveyor screw is left exposed in the bottom of the retort and by reason of its length severe bending stresses are exerted in the intermediate portion of this section by the upward wedging action of the coal which becomes packed beneath the screw.

One object of the present invention is to provide a new and improved conveyor screw for underfeed stokers which is particularly adapted to withstand the strains to which it becomes subjected when used in a stoker for a Scotch marine boiler.

More specifically stated, the invention aims to provide an underfeed stoker having a conveyor screw composed of two axially aligned sections which are joined within the furnace retort by a coupling permitting of lateral flexure of the screw sections relative to each other.

Another object is to provide a novel bearing for supporting the inner end of the conveyor screw in an underfeed stoker whereby clogging of the bearing by accumulating coal dust is effectually avoided.

Other objects and advantages of the invention will become apparent from the following detailed description taken in connection with the accompanying drawing, in which,

Figure 1 is a vertical sectional view of a boiler equipped with a stoker embodying the features of the present invention.

Fig. 2 is a fragmentary plan view of the stoker retort.

Fig. 3 is a sectional view taken along the line 3—3 of Fig. 1.

In the exemplary form shown in the drawing, the invention is embodied in a boiler of the Scotch marine type having a long and relatively shallow horizontal combustion space 5 in which a bed of fuel is supported by a retort comprising an upwardly opening trough 6 whose upper edges merge into perforated ledges 7 constituting grates. To conform to the shape of the combustion space, the retort is made relatively shallow and its top opening is long and narrow.

Communicating with the lower portion of the retort and extending forwardly from its front wall 55 is a tubular projection 8 into which is received

a horizontal conduit 9 which extends forwardly through the front wall of the furnace and communicates with a hopper 10 from which coal is fed in the operation of the power driving mechanism 11 of the stoker.

Within the conduit 9 is a rigid shaft 12 carrying flights 13 of a diameter slightly less than the conduit 9 and defining a screw for conveying coal from the hopper 10 along the conduit and into the retort in the normal rotation of the stoker motor 14. The outer end of the shaft 12 is rotatably supported in the usual way by the frame of the power unit 11 and the inner end projects a short distance into the lower portion of the retort.

Longitudinally aligned with the screw above described is a second rigid shaft 15 of shorter length disposed wholly within the retort and having flights 16 of an inclination similar to the flights 13 but of a smaller diameter and preferably tapering slightly toward its rear end. The latter end of the shaft 15 is received in a cylindrical bearing socket 17 defined by the rear concave wall of the retort and carries a screw flight 18 which rotates loosely in the socket.

At its forward end, the shaft 15 is joined to the adjacent end of the shaft 12 by a coupling 19 which preferably permits some degree of universal movement between the two shafts so that the conveyor screw may flex slightly at a point near the center of the retort thereby relieving the severe lateral stress to which this part of the screw becomes subjected while forcing coal upwardly through the retort opening. It will be observed that the bearing at the rear of the shaft 15 permits of such limited upward movement of the coupling 19.

Inasmuch as the rear section of the conveyor screw is of relatively smaller diameter and tapers toward its rear end, the capacity of this section is correspondingly decreased with the result that the coal will be distributed evenly along the entire length of the retort opening thereby avoiding restriction of the shallow combustion space.

In order to prevent dust and small particles of coal from clogging the rear bearing of the conveyor, the screw flight 18 is inclined reversely to the flights 16 and therefore operates automatically in the normal rotation of the conveyor screw to withdraw from the socket any particles tending to accumulate therein. The provision of such a means for preventing clogging is particularly important in the present instance in view of the fact that some degree of play must be provided

for at the bearing in order to allow for relative flexing of the bearing sections.

By forming the conveyor screw in two rigid sections coupled together as above described, it will be apparent that I have eliminated the danger of breaking the conveyor screw by packing of coal beneath the screw when the same is used in such a long retort as is required in furnaces of the Scotch marine type. Assembly of the conveyor is also greatly facilitated because it is unnecessary to align its supporting bearings.

I claim as my invention:

1. In an underfeed stoker, the combination of an upwardly opening retort having an inwardly opening bearing socket in its rear wall, a rotary screw shaft projecting into the lower portion of said retort with its inner end disposed in said socket, and flights on said inner end rotatably supporting said end in said socket and inclined to convey accumulating coal dust out of said socket during rotation of said screw shaft in a direction to advance coal into said retort.

2. In an underfeed stoker, the combination of an upwardly opening retort having a rear wall, a bearing sleeve in said rear wall opening to said retort, a rotary screw projecting into the lower portion of said retort and having its inner end extending into said sleeve, said screw being operable to advance fuel into said retort toward said wall, and means on said inner end of said screw rotatably supported in said sleeve and operable as an incident to the normal rotation of said screw to expel from said sleeve any fuel tending to accumulate therein.

3. In an underfeed stoker, the combination of an upwardly opening retort having an inclined rear wall formed with an inwardly opening cylindrical bearing socket substantially closed at its outer end, a shaft projecting into said retort with its inner end extending into said socket, flights on said shaft defining screw means for advancing fuel into said retort toward said rear wall, and reverse flights on said inner end of said shaft rotatably supported in said socket and defining screw means for expelling any fuel tending to accumulate in said socket.

4. In a stoker, the combination of a retort having an inlet opening in one side thereof, a first screw extending through said opening into said retort, a second screw in said retort flexibly coupled at one end to the inner end of said first screw, a bearing in said retort, and reverse screw flights on the other end of said second screw and

loosely supported for rotation in said bearing to prevent coal dust from accumulating in said bearing.

5. In an underfeed stoker, the combination of a horizontal retort discharging upwardly and having a horizontal inlet opening in one wall and an inwardly opening bearing socket in an opposite wall, a rotary screw shaft extending through said opening into said retort, and reverse screw flights on the inner end of said shaft and rotatably supported in said socket to prevent the packing of fuel in said socket, an intermediate portion of said shaft being positioned above the bottom of said retort and having a flexible coupling interposed therein.

6. In an underfeed stoker, the combination of a horizontal retort discharging upwardly and having a horizontal inlet opening in one wall and an inwardly opening bearing socket in an opposite wall, a first shaft with rotary screw flights extending through said opening into said retort, a second shaft with rotary screw flights having a lead in the same direction as said first mentioned flights, and extending above the bottom of said retort and in substantial axial alignment with the inner end of said first mentioned shaft, a universal coupling connecting the adjacent ends of said shafts, and reverse screw flights on the remote end of said second shaft rotatably supported in said socket and operative to prevent the packing of fuel in said socket.

7. In an underfeed stoker, the combination of a horizontal retort discharging upwardly and having a horizontal inlet opening in one wall and an inwardly opening bearing socket in an opposite wall, a first shaft with rotary screw flights extending through said opening into said retort, a second shaft with rotary screw flights having a lead in the same direction as said first mentioned flights, and extending above the bottom of said retort and in substantial axial alignment with the inner end of said first mentioned shaft, a universal coupling connecting the adjacent ends of said shafts, the flights on said second shaft being smaller in diameter than said first mentioned flights and being tapered toward the end of said second shaft remote from said coupling, and reverse screw flights on said remote end of said second shaft rotatably supported in said socket and operative to prevent the packing of fuel in said socket.

WARREN DEAN BURTON.
